WITNESS:

UNITED STATES PATENT OFFICE.

HERMAN F. MIETZ, OF FRANKLINVILLE, NEW JERSEY.

BANJO.

Application filed April 30, 1925. Serial No. 27,022.

This invention relates to banjos, and an object of the invention is to provide a banjo structure which will permit the full natural tones of the banjo to be created while playing the banjo with the use of a resonator or amplifier of types such as have come into universal use.

It is a well known fact that when using amplifiers or resonators with banjos, the music is increased in volume or amplified but the true tones of the banjo are distorted, owing to the impeding of the outlet for the music.

It is an object of the present invention to provide a banjo structure in which outlets for the music are provided in such manner as to permit the full and true tones of the banjo to be provided with the use of an amplifier.

Another object of the invention is to provide a novel form of amplifier or resonator for use in connection with a particular form of banjo head.

Other objects of the invention will appear in the following detail description, and in the accompanying drawings wherein:

Figure 1—is a plan of a banjo constructed in accordance with this invention with part of the drum head broken away.

Figure 2—is a cross section through the banjo.

Figure 3—is a fragmentary top plan of a modified form of the invention.

Figure 4—is a fragmentary cross section through the modified form of the invention.

Referring more particularly to the drawings in Figs. 1 and 2, 1 indicates the banjo rim which is made or constructed in the usual manner of the construction of the wood rims of banjos, and it has a sound ring 2 attached to its upper edge.

The ring 2 comprises the vertical section 3 and the horizontal section 4 which latter section is attached in any suitable manner to the upper edge of the rim 1 and overhangs the cut-away upper corner 5 of the rim 1.

The portion of the horizontal part 4 of the ring 2 is provided with a plurality of circumferentially spaced openings 6 which open out into the cut-away portion 5, and the vertical part 3 of the ring 2 is provided with a plurality of circumferentially spaced openings 7.

The head carrying ring 8 which is of approved construction, is mounted upon the ring 2 and has an annular shoulder 9 on its inner surface which rests upon the perimeter of the horizontal portion 4.

The banjo head 10 which is of the usual

type of skin is carried by the hoop structure 11 which is also of the approved type used in the construction of banjos, and the hoop engages over the outer surface of the ring 8, as clearly shown in Figure 2 of the drawings. The ring 8 is tightly clamped by means of the clamping bolts 12 which extend through the laterally projecting resonator ring 13. The ring 13 replaces the usual type of brackets which are carried by the banjo rim 1 and it has its upper surface concavely curved transversely, as shown at 14, to act as the top of a resonator or amplifier and to deflect the music which issues through the openings 6 and 7. By providing suitable openings 15 in the resonator ring 13, the clamping bolts 12 may extend therethrough, and the clamping nuts 16 which are threaded on the clamping bolts engage against the under flat surface 17 to tightly clamp the head in position.

In Figures 3 and 4 of the drawings, a modified form of the invention is shown in which the wood rim 20 is provided with an annular groove 21 near its upper end and the skirt 22 of the head carrying ring 23 overhangs this annular groove. A plurality of openings 24 are cut or drilled at circumferentially spaced points through the rim 20 and open out into the groove 21 to permit the escape of the sounds from beneath the skin head of the banjo.

From the foregoing description taken in connection with the accompanying drawings, it will be apparent that in the preferred form of the invention, the rim 1 and ring 2 combine to form a rim structure which serves a similar and substantially the same function as the grooved rim structure illustrated and described in the modified form of the invention, and that the various openings which open into the cut-out portion 5 of the rim 1 or the openings which open into the annular groove or cut-out portion 21 in the rim 20, serve to conduct the sound or music into these grooves and outwardly of the outer perimeter of the rim.

In the preferred form illustrated in Figures 1 and 2 of the drawings, the vertical portion 3 of the ring 2 and the head carrying ring 8 combine to provide an annular sound chamber beneath the head 10 and from which the sound issues through the openings 6.

In both forms, it will be seen that sound outlets have been provided from inwardly of the heads of the banjo to permit the issuing of the sounds and it will be apparent that

when the banjo is closed by means of an amplifier or resonator (not shown) of approved types, one of which is shown in my companion application, filed January 2, 1925, Serial No. 231, that the true tones of the banjo will be permitted to issue from these outlets, as well as through the openings 15 in the ring 13 through which the sounds are directed from the amplifier indicated in dotted lines in Figure 2.

What I claim is:—

1. In a banjo, a supporting head rim, a skin head and clamping ring therefor, a sound outlet ring operatively carried by the supporting head rim and being located beneath the skin head, a skin head carrying ring with means for supporting it on the sound outlet ring, the skin head being clamped between the skin head carrying ring and the clamping ring, said sound outlet ring having a plurality of outlet openings, and means for retaining and holding said parts on said rim.

2. In a banjo, the combination with an annular rim structure, of a skin head and outer skin supporting ring and clamping ring therefor, a sound outlet ring carried by the annular rim structure and positioned concentrically within said outer skin supporting ring beneath the said skin head in spaced relation thereto, said sound outlet ring comprising right angularly disposed flange portions, each provided with a plurality of circumferentially spaced sound outlet openings, the outlet openings in one of the flange portions being positioned outwardly of the adjacent outer edge of said annular rim, the flange portion of said outlet ring being spaced from the inner surface of the skin supporting ring, said outlet ring having an apertured flange portion and being positioned intermediate said other flange portion and outer ring substantially as described.

In testimony whereof I affix my signature.
HERMAN F. MIETZ.
